2,836,404SECONDARY-STAGE THROTTLE CONTROL FOR
A MULTI-STAGE CARBURETOR

Harold A. Carlson, Brentwood, and Olin J. Eickmann, Normandy, Mo., assignors, by mesne assignments, to ACF Industries, Incorporated, New York, N. Y., a corporation of New Jersey

Application May 3, 1956, Serial No. 582,421

8 Claims. (Cl. 261—23)

This invention relates to multi-stage carburetors, and more particularly to the type having each stage separately controlled by an individual throttle valve wherein the primary stage throttle is manually controlled, and the secondary stage throttle automatic in operation.

According to this invention, the separate stages are individually controlled by separate throttles arranged for operation so as to match the carburetor capacity with engine requirements. In order to do this, the primary throttle is mechanically interconnected with the automatic secondary throttle in such a way as to control the initial opening of the secondary throttle with respect to the degree of opening of the primary throttle and perform a sequential closing operation in which the secondary throttle is first moved to the full-closed position as the primary throttle returns from the full-open position.

The automatic secondary throttle is of the type which is so mounted as to be unbalanced to close by the action of suction thereon. The automatic opening of the secondary throttle is performed by an unbalanced weight acting in the opposite direction to rotate the valve against the force of suction.

The objects and advantages of this invention will be more clearly understood as hereinafter described in the detailed description, taken with the accompanying drawings, in which:

Fig. 1 is a view illustrating a conventional four-barrel carburetor in side elevation.

Fig. 2 is a view in side elevation of the opposite side of the four-barrel carburetor shown in Fig. 1.

Figs. 3 and 4 are fragmentary views of the carburetor in Fig. 2, showing the mechanical gearing between the throttle shafts and illustrating two positions during operation of the carburetor.

Fig. 5 is a fragmentary view of the carburetor in Fig. 1, showing the gearing on the opposite side and the position of the parts during operation of the carburetor.

Fig. 6 is a view in vertical section, taken through the carburetor as shown in Fig. 2, illustrating one of each pair of primary and secondary mixture conduits.

The invention is illustrated as applied to a multi-barrel, multi-stage carburetor of the type commonly referred to as a four-barrel. The details of this type of carburetor are generally shown in many patents; for example, the patent to Carlson et al., No. 2,715,522 of August 16, 1955. Since this invention is primarily concerned with a mechanism for controlling the operation of the throttles, details of the fuel system will not be described.

Fig. 1 shows a carburetor of the type above referred to, having an air horn section 1 with a fuel connection 2, and a fuel bowl section 3 with a flange 4 by which the carburetor may be attached to the intake manifold of the engine.

Referring to Fig. 6, the carburetor has a pair of primary mixture conduits 7, and a pair of secondary mixture conduits 8, only one of each of which is shown,

but, since each pair is identical, a description of one will serve for both in each instance. Within the air horn section 1 is journaled a chokeshaft 9 mounting a choke valve 10, which controls the entrance of the air horn communicating with the primary mixture conduits or barrels. Within the main venturi 12 is a primary venturi 13. A main fuel nozzle 14 opens into the primary venturi 13. It will be understood that the fuel supply within the fuel bowl section 3 communicates with the main fuel nozzles 14 by way of suitable main fuel passages connecting the nozzles and a metered inlet in the fuel bowl.

The outlet of the mixture conduit 7 is controlled by a throttle valve 15 mounted on the throttle shaft 16, which is suitably journaled in the fuel bowl section 3 so as to pass through both of the primary mixture conduits 7. Adjacent one edge of the throttle 15 are located the usual low-speed fuel ports 17 and 18, the latter of which is suitably controlled by an adjustable needle valve 19 in a manner well understood in the art. Likewise, these ports communicate with the fuel passage to the main fuel nozzle 14 through a series of vertical passages 20 and a horizontal, interconnecting passage 21, all in a manner understood in the art.

Within the secondary mixture conduit is a main venturi 23 in which is concentrically arranged a primary venturi 24 having a main fuel nozzle 25. This fuel nozzle is also interconnected with the supply of fuel within the fuel bowl section 3 by a suitable main fuel passage. The outlet of the secondary mixture conduit 8 is controlled by a throttle valve 26 mounted on a throttle shaft 27 suitably journaled in the fuel bowl section 3 and passing through both secondary mixture conduits 8. It should be noted that the throttle valve 26 is unbalanced to be closed by suction, and the degree of unbalance is illustrated by the distance between the center line X—X of the secondary throttle shaft 27 and the center line Y—Y of the secondary mixture conduit 8.

Fig. 2 shows the opposite side of the carburetor illustrated in Fig. 1, which, in turn, mounts an automatic choke housing 30 containing a suction and temperature operated mechanism such as shown in the patent to Coffey 2,325,372. The control arm 31 from this mechanism is connected by means of a link 32 and arm 33 with the chokeshaft 9. The opposite end of the chokeshaft 9 carries an arm 35 connected by way of a link 36 with one end of a lever on the fast idle cam mechanism 37 which is mounted on the stub shaft 38. Also mounted on the stub shaft 38 is a weighted latch member 39. A shoulder 40 on the lower edge of the arm 39 abuts one edge of a dog 41 on a disc-like lever 42 secured to the secondary throttle shaft 27. One end of the lever 39 carries weight W, while the other is formed with a cam follower member 43 positioned for contact by the cam 44 formed integral with lever 45 secured to the primary throttle shaft 16.

On the end of the lever 45 is an inturned lug 46 positioned to engage the arm of the fast idle cam mechanism 37 when the primary throttle is opened fully, so as to partially open the choke valve 10 to perform the unloading function.

Primary throttle shaft 16 also carries a suitable actuating lever 48 provided with a hole 49 for connection with an actuating rod. A suitable threaded lug 50 receives an idle set screw 51 for adjusting the closed position of the primary throttles. Lever 48 is connected by way of a rod 53 with one end of a pivoted arm 54 positioned to operate the plunger of the accelerating pump 55.

The opposite end of the primary throttle shaft 16, as shown in Fig. 2, has fixed thereto an arm 60 connected by a link 61 in a slot 62 of arm 63 freely rotatable on the secondary throttle shaft 27. One face of the arm 63,

indicated as 64, is arranged in abutting relation with an inturned lug 65 on an arm 66 secured to the secondary throttle shaft 27. The opposite end of the arm 66 carries a weight 67 which continuously urges the secondary throttles 26 in an opening direction. A cam surface 70 on the lever 63 slidably engages with a cam surface 71 on a lever 60 when both throttles are in the closed position.

Operation

When the primary throttles 15 are closed, the secondary throttles 16 are held closed by the latch 40, 41 at one end of the secondary throttle shaft 27 and by the engagement between the cam surfaces 70, 71 which hold lever 63 in a position so that face 64 abuts the lug 65 on the lever 66 at the other end of the shaft 27.

During opening movement of the primary throttle, the cam faces 70 and 71 disengage, as shown in Fig. 3, and the end of link 61 in slot 62 slides into the position engaging the end of the slot 62 so as to hold the secondary throttles closed. Further movement of the primary throttle moves the arm 63 so as to disengage face 64 from lug 65. Simultaneously, cam 44, shown in Fig. 1, engages inturned lug 43, lifting the latch arm 39 so as to disengage the abutting surface 40 from the lug 41, all as shown in Fig. 5. This occurs, preferably, after the primary throttle has reached a point about 10 degrees from wide open.

After the primary throttles have reached this stage in their opening movement, the secondary throttles will be unlocked by the mechanisms described on each end of the secondary throttle shaft 27 so as to permit the weight 67 to open the unbalanced secondary throttles against suction. The degree of opening, however, will be under control of the movement of the primary throttle, as illustrated in Fig. 3.

As the primary throttles 15 move to the wide-open position, arm 63 is permitted to rotate to the position shown in Fig. 4, which permits full opening movement of the secondary throttles.

As will be apparent from Fig. 4, when the primary throttles start to close from wide-open position, link 61 initiates closing movement of the secondary throttles by engagement with the left end of slot 62. Continued closing of the primary throttles beyond the position shown in Fig. 5 disengages cam 44 from follower 43, permitting the latch 39 to drop into engagement with the lug 41 on the secondary throttle shaft. Further closing movement of the primary throttles beyond the position shown in Fig. 3 engages the face 64 with lugs 65, forcing the secondary throttles closed as the lever 60 and link 61 pass the dead-center position. The length of link 61 can be adjusted so that the secondary throttles are tightly closed at this stage of operation of the primary throttles. This permits the latch 39 to drop fully into engagement with the lug 41 to lock the secondary throttles closed. Thereafter, the carburetor works on the primary throttles only within the range permitted by the location of the unlatching cam 44, as illustrated in Fig. 5.

The above described mechanism is such that the secondary throttles are securely closed on closing of the primary throttles, and are held in that position by mechanism on opposite sides of the secondary throttle shaft, as well as the action of suction acting upon the secondary throttles 26. This will eliminate any undesirable leakage through the secondary barrels during idling. After the mechanism at opposite ends of the secondary throttle shaft 27 is unlocked, as shown in Figs. 3 and 5, the secondary throttles are then free to open under the force exerted by the weight 67, which opposes the degree of suction acting on the unbalanced throttles 26.

On the other hand, the force of suction is sufficient to hold the secondary throttles tightly closed at idle and in the part-throttle range of primary throttle operation, which means that the primary linkage and throttle re-

turn spring are relieved of any interference with their operation. In other words, it requires no force from the primary operating linkage to hold the secondary throttles closed. Accordingly, it is not necessary to use an excessively strong throttle return spring on the primary throttles or adjust the linkage between the two pairs of throttles in order to allow the primary throttles to return to the proper position for idle when manual pressure on the accelerator pedal is released.

When the choke mechanism is in the "on" position, the secondary throttles will normally be locked closed, but full opening movement of the primary throttle releases the latch 40, 41, permitting the throttles to drop open, and opens the choke valve simultaneously therewith.

A structure has been described which will fulfill all the objects and advantages of the present invention, but it is contemplated that other modifications will occur to those skilled in the art which come within the scope of the appended claims.

We claim:

1. In a multi-stage carburetor, the combination of primary and secondary mixture conduits, a manually controlled primary throttle in said primary mixture conduit, a secondary throttle in said secondary mixture conduit unbalanced to close by engine suction, latch means releasable by said primary throttle to retain said secondary throttle closed within the initial range of opening movement of said primary throttle, and biasing means instantly urging said secondary throttle in an opening direction upon release of said latch.

2. In a multi-stage carburetor, the combination of primary and secondary mixture conduits, a manually controlled primary throttle in said primary mixture conduit, a secondary throttle in said secondary mixture conduit unbalanced to close by engine suction, biasing means tending to open said secondary throttle against the force of suction, and means including a latch controlled by said primary throttle for positively closing and locking said secondary throttle during the initial closing movement of said primary throttle from full open position.

3. In a multi-stage carburetor, the combination of primary and secondary mixture conduits, a manually controlled primary throttle in said primary mixture conduit, an automatically operated secondary throttle in said secondary mixture conduit unbalanced to close by engine suction, latch means for retaining said secondary throttle closed, mechanism operated by said primary throttle during its opening movement to release said latch so as to permit said secondary throttle to open, biasing means urging said secondary throttle to open, and a lost motion linkage means between said throttles operative during closing of said primary throttle and, after said latch is freed by said primary throttle operated means, to return said secondary throttle to closed position.

4. The combination defined in claim 3, wherein said mechanism includes a lost motion linkage connection between said throttles operating only during part of the closing movement of said throttles, and a positive driving connection operating during the final closing movement of said throttles.

5. In a multi-stage carburetor, the combination of primary and secondary mixture conduits, a manually controlled primary throttle in said primary mixture conduit, a secondary throttle in said secondary mixture conduit unbalanced to close by engine suction, a latch to hold said secondary throttle closed, means directly connecting with said secondary throttle for urging said secondary throttle open against the force of suction, means movable with said primary throttle to release said latch, a lever movable with said primary throttle, a second lever fixed on and urging said secondary throttle to open, a third lever rotatable with respect to said secondary

throttle having a face in abutting relation with said second lever, a slot in said third lever, and a rod positively moved by said first lever and having a lost motion connection within the slot in said third lever.

6. The combination defined in claim 5, in which said first lever and said third lever have interengaging surfaces in sliding contact for maintaining the abutting surfaces on said second and third levers in contact with one another so as to prevent full opening movement of said secondary throttles during part of the range of movement of said primary throttles.

7. In a multi-stage carburetor, the combination of primary and secondary mixture conduits, a manually controlled primary throttle in said primary mixture conduit, a secondary throttle in said secondary mixture conduit unbalanced to close by engine suction, latch means releasable by said primary throttle to retain said secondary throttle closed within the initial range of opening movement of said primary throttle, biasing means constantly urging said secondary throttle in an opening direction upon release of said latch, a choke mechanism including a choke valve operatively connected to a rotatable fast idle cam, and means operable responsive to opening movement of said primary throttle to rotate said cam and to release said latch for unloading.

25

8. In a multi-stage carburetor, the combination of primary and secondary mixture conduits, a manually controlled primary throttle in said primary mixture conduit, a secondary throttle in said secondary mixture conduit unbalanced to close by engine suction, latch means releasable by said primary throttle to retain said secondary throttle closed within the initial range of opening movement of said primary throttle, biasing means constantly urging said secondary throttle in an opening direction upon release of said latch, a choke mechanism including a choke valve operatively connected to a rotatable fast idle cam, and means operable responsive to opening movement of said primary throttle to rotate said cam and to release said latch for unloading, said latch being pivotally unbalanced to lock said secondary throttle by gravity.
